G. JONES,
Sash Holder.
N° 34,967. Patented Apr. 15, 1862.

Fig: 2

Fig: 1

UNITED STATES PATENT OFFICE.

GEORGE JONES, OF PEEKSKILL, NEW YORK.

IMPROVED WINDOW-SASH ADJUSTER.

Specification forming part of Letters Patent No. 34,967, dated April 15, 1862.

To all whom it may concern:

Be it known that I, GEORGE JONES, of Peekskill, in the State of New York, have invented a new and useful Machine for Moving and Adjusting Window-Sash in the Frame; and I do hereby declare that the following is a full, clear, and exact description of the construction and operation of the same, reference being had to the accompanying drawings, making part of this specification, and to the letters of reference marked thereon.

Figure 1 of the accompanying drawings represents the sash and frame as they appear to the eye, in which only the lower ends of the rods *b b* and the lower rests or supports of the rods *a a* are visible. Fig. 2 is a vertical section of the sash and frame, in which—

A represents the sash, in the sides of which are grooves *B B*. In these grooves the rods *b b* are fastened by means of the rests or supports *a a* and *f f* to the frame, and to the sash *A* are fitted the gages *h h*, made of any suitable metal, and to these gages are attached the curved metallic springs *i i*, which act at both ends on the rods *b b* and hold the sash *A* steadily to the rods *b b*, and while allowing the sash to move freely and easily up and down retain it steadily and firmly at any point or place at which the hand moving the same may be withdrawn.

Fig. 2 represents the upper sash. The lower sash is moved up and down in the same way by similar rods, springs, gages, &c., con-

structed in like manner, the sash always remaining stationary whenever and wherever the hand moving it is withdrawn. The rod has been used for a similar purpose before; but the curved metallic spring attached to a gage fastened to the sash and working at the ends on the rod, as above described, is the original invention of the undersigned.

My window-adjuster is simple of construction, easy of action, saves labor and material in making window-frames, is very durable, not easily put out of repair, and when needing repair is easily got at for that purpose. It works without noise, and requires but little force to work it with ease. It also saves time in being applied to new buildings, and may be used in old ones as a substitute for the weights and pulleys or other apparatus. It may be applied to windows of all sizes, and is very useful, steadyng the window.

What I claim as my invention, and desire to secure by Letters Patent, is—

The combined application of the curved metallic spring, rod, and gage, constructed in grooves in the sides of the window-sash, to the moving and adjusting of the sash within the frame, by means of which both the upper and lower sash may be moved up and down in the frame at pleasure.

GEO. JONES.
